TELEFACSIMILE SCANNER

Arthur C. Rustad, Brooklyn, N. Y., assignor to
Press Wireless, Inc., Chicago, Ill., a corpora-
tion of Delaware

Application June 14, 1938, Serial No. 213,584

18 Claims. (Cl. 178—14)

This invention relates to telefacsimile apparatus and more especially to such apparatus as is used for scanning a longitudinally movable web or strip.

5 A principal object of the invention is to provide an improved structure of telefacsimile scanner which is suitable for use in continuous service such for example as news distribution and the like.

10 Another principal object is to provide an improved recorder for telefacsimile signals.

A further object is to provide a novel method and apparatus for scanning a longitudinally movable web or record sheet by forming the sheet or

15 web to arcuate shape across the width, and then scanning the convex surface of the sheet.

A still further object is to provide a novel method of supporting and feeding a longitudinally movable record strip in a step-by-step motion past a rotatable scanning device.

20 A feature of the invention relates to a scanning mechanism wherein the scanning device is rotated around the convex periphery of a curved support which carries the recording web or strip.

25 Another feature relates to a novel form of paper feed drive for a telefacsimile scanner or the like.

Another feature relates to an improved manner of shaping a normally flat web or record 30 sheet into transversely curved form and feeding it in its curved form past a continuously rotating scanning member.

35 A further feature relates to an improved paper feed and moisture control arrangement for a continuous strip telefacsimile scanner.

40 A still further feature relates to the novel organization, arrangement and relative location of parts which constitute an improved telefacsimile recorder which is compact in form and rugged in construction thus rendering it particularly useful for continuous operation, for example in news distribution and the like.

45 Other features and advantages not specifically enumerated will be apparent after a consideration of the following detailed descriptions and the appended claims.

50 While certain particular embodiments of the invention will be illustrated, it will be understood that this is done merely for explanatory purposes and not by way of limitation and various changes and modifications may be made therein without departing from the spirit and scope of the invention. In the drawings:

55 Fig. 1 is an elevational view, particularly in

section, of a telefacsimile recorder embodying features of the invention.

Fig. 2 is a sectional view of Fig. 1 along the line 2—2.

Fig. 3 is a top plan view of Fig. 1.

Fig. 4 is an enlarged detail view of one of the paper feed idler rollers with its locking and releasing mechanism.

Fig. 5 is a sectional view of Fig. 4 along the line 5—5.

Fig. 6 is an enlarged view of one of the feed rollers and the manner of mounting and fastening to the flexible shaft.

Fig. 7 is a sectional view of Fig. 6 along the line 7—7.

Fig. 8 is a sectional view of Fig. 1 along the line 8—8.

Fig. 9 is a sectional view of Fig. 1 along the line 9—9.

Fig. 10 is an enlarged plan view of the stylus 20 and stylus holder.

Fig. 11 is a front view of Fig. 10.

Fig. 12 is a sectional view of a modification of the invention.

Referring to Fig. 1, there is shown a telefacsimile recorder the scanner or recording portion of which may be supported on the top wall 1 of an enclosing box or housing 2. Top 1 is provided with a continuous slit 3 of semi-circular shape to allow the recording web or paper strip 4 to 30 emerge, therethrough in transversely arcuate form as will be described hereinbelow.

Suitably secured to the top 1 is a cylindrical drum consisting of a ring 5 of insulation material such as fibre, hard rubber, Bakelite or the like, and a cylindrical metal flange 6; flange 6 being fastened to ring 5 so that the outer or convex peripheral faces of members 5 and 6 are flush with each other. The periphery of member 6 is provided with a series of spaced openings 7 and mounted adjacent each opening is a knurled feed roller 8, the feed rollers being driven in unison by a flexible shaft 9 arranged in circular form around the interior of member 6. As shown in detail in Figs. 6 and 7, each feed roller is provided on opposite sides with integral bearing members 10, 11, for rotation in the associated bearing brackets 12, 13, fastened to the inner face of member 6. The flexible shaft 9 passes through each roller which is fastened thereto by a set 50 screw 14.

On the opposite diameter to one of the feed rollers is a ratchet wheel 15 which is fastened to the ends of the flexible shaft 9 in a manner similar to the fastening of the feed rollers thereto. 55

Shaft 9 is of closely coiled spring wire such as is ordinarily used for flexible shafting, and in order to avoid undesirable torsion in the shaft, the end portions adjacent the ratchet wheel 15 are 5 twisted slightly in opposite directions as indicated by the arrows, it being understood of course that once the shaft is fastened to the ratchet wheel and to the several feed rollers, that the latter are all driven in the same direction with 10 respect to the longitudinal axis of ring 5 thus pulling the paper 4 in the direction of the arrow (Fig. 1).

Mounted in radial alignment with feed rollers 8 15 are corresponding idler rollers 16, each of which is rotatably mounted in a bracket 17 swiveled at 18 on a corresponding support 19 fastened to top 1. Each idler roller is adapted to be held in frictional contact with the record strip 4 by a spring 20 (Fig. 4). For the purpose of locking 20 the idler rollers against the record strip, there is provided a ring 21 the outer peripheral face of which has a circumferential guiding groove to receive slidably an arcuate lip 22 on member 23 the latter being fastened to member 19 by screws 24. 25 Preferably, there is a guiding member 22 mounted on each of the members 19 as shown in Fig. 3. Ring 21 is slidably rotatable on member 19 and is guided by the lips 22. The inner peripheral face of ring 21 adjacent each of the brackets 17 30 is provided with an inclined key-way or cam slot 25 (Fig. 5) in which rides the key 26 carried by bracket 17. Consequently, merely by turning the ring 21 in one direction or the other, the idler rollers can all be moved in unison towards or 35 away from the recording strip 4.

Each of the members 19 has its inner face provided with a slot 27 to receive the outer margin of a flat rotatable ring 28. Ring 28 is supported for anti-frictional rotation on a plurality of sets 40 of V-shaped rollers 29, 30, which are rotatably mounted on the associated member 19 so that their bearing edges engage the opposite sides of ring 28 to support the latter during its rotation. If desired, ring 28 may be provided on opposite 45 sides with shallow circumferential grooves wherein the rollers 29, 30 may ride. Attached to the inner margin of ring 28 and at diametrically opposite points thereof, are two stylus holders 31, 32, each carrying a stylus 33 adjustably fastened in place. As shown in Figs. 10 and 11, the stylus 33 is imbedded in a curved shoe 33^a of insulating material, the shoe being fastened to an arm 33^b which is slidably mounted in a slot 33^c in the holder 31. The outer or recording end 50 of the stylus is exposed and if desired, may project slightly beyond the shoe 33^a. Preferably however, the exposed end is flush with the face of the shoe. A removable plate 33^d is fastened to the member 31 to allow the arm 33^b to slide in 55 the slot 33^c. The stylus is normally resiliently held against the recording strip 4 by means of a spring 33^e having one end fastened to member 31, and the other end is provided with a threaded portion 33^f through which is adjustably threaded 60 the stop 33^g. Arm 33^b is also provided with a pin 33^h for engagement with a track member 33ⁱ. As shown in Fig. 3, the track 33ⁱ is made in two telescoping sections 33^j and 33^k which are supported by arms 33^l from the member 6. Arms 65 33^j and 33^k are telescoped so as to vary the peripheral extent of the track around the member 6. As shown in Fig. 3 the ends of the sections 33^j and 33^k are inclined so that when they engage the pins 33^h the stylus is cammed radially 70 outwardly away from contact with the record 75

strip. Thus as shown in Fig. 3, just as the carrier 32 is about to leave the strip 4, the end of track 33^k engages pin 33^h thus preventing undesirable contact between the stylus and the member 6 when the stylus leaves the recording 5 strip.

As will be seen further in Fig. 1, the stylus ring 28 is so mounted that each stylus is in registry with the ring electrode 34 embedded in the periphery of ring 5. Electrode 34 may be of carbon 10 or other suitable conductive material and connection may be made thereto by means of a suitable binding post 35.

Ring 28, while it surrounds ring 5 is spaced therefrom so as to allow the record web or strip 15 4 to pass freely, it being understood that the said strip is of any material well known in the facsimile art capable of producing a permanent record when current corresponding to the telefacsimile signals is passed from the stylus 33 20 through the record strip to the electrode 34. For example, the record strip 4 may be of chemically treated paper, or the like well known in the facsimile art. Under certain conditions, it is desirable to preserve the moisture content of the record strip as nearly uniform as possible, and for this purpose the record strip is stored in the form of a roll 36 wound on a suitable core 37 supported for rotation on studs 38. Preferably, a friction brake is provided so that the roller does 30 not unroll too freely. This brake may take the form of a series of springs 39 which frictionally engage the inner end walls of the core 37 so that there is always a slight tension on the record strip to take up any slight slack that may tend to 35 exist therein. Any well known slack take-up means may be employed as will be obvious to those familiar with the web-feeding art.

The roll is enclosed in an air-tight chamber or 40 humidor preferably of sheet metal and comprising a cylindrical storage section 40 closed at both ends by removable cover plates 41, 42, to allow the roll to be inserted. The cover plates may carry the roller stud bearings 38. The section 40 is provided with a longitudinal opening 43 45 through which the record strip passes. The humidor also has a curved trough-like section 44 shown in cross section in Figs. 1 and 9, this section being formed of a sheet metal member having a curved wall closed at the front by a 50 removable cover plate 45 so that the paper can be conveniently threaded through the slot 3. The paper trough may be fastened to the top 1 by means of suitable flanges 46 and preferably the humidor is such that when the cover 45 is 55 fastened in place the paper is enclosed in a substantially moisture-proof manner except for the small clearance at the slot 3 through which paper is fed.

I have found that the feeding of the paper 60 is best achieved by maintaining the part of the paper between the roll and the slot 3 out of contact with the walls of the trough-like portion 44 of the humidor, and preferably the parts 65 are so arranged that the paper is unreeled from the roll 36 at a point laterally displaced from the slot 3 as shown more clearly in Figs. 1, 8 and 9 of the drawing. In other words, the paper between the point where it is paid off from the roll 70 and the point where it passes through the slot 3 is freely suspended within the humidor housing. This is particularly important where moist or damp paper is employed since otherwise the adhesion between the paper and the walls of the 75

humidor might interfere with the proper feeding movement thereof.

In order to effect the timed feeding of the record strip with respect to the recording movement of the stylus 33 and in order to revolve the stylus, there is provided a suitable motor 47 which may be of the synchronous type and mounted on the top 1 interiorly of the ring 5. The motor shaft 48 is connected through suitable reduction gearing 49 and appropriate bevelled gears 50 to a countershaft 51 which is mounted for rotation in a suitable bearing bracket 52. Shaft 51 has fastened thereto a pinion 53 which meshes with the rack teeth 54 formed in the outer peripheral surface of the ring 28. Ring 28 therefore serves not only to carry the recording stylus but also serves as a circular rack which is driven by the pinion 53. Thus the stylus 33 is revolved around the axis 20 of the ring 5 at a continuously uniform rate of speed determined by the speed of recording. Inasmuch as the stylus 33 when it is recording, is in actual contact with the record strip 4 it is important that the said strip be fed in a step-by-step movement and that this feeding occur only when the stylus is out of contact with the strip. For this purpose, there is provided a pawl 54 which engages the ratchet wheel 53. Pawl 54 is pivotally carried on an arm 55 which is mounted for vertical reciprocal motion in a bracket 56. Arm 55 is normally pressed downwardly by means of a spring 57 located between the bracket 56 and a suitable shoulder 58 on the said arm. Arm 55 also carries at its lower end a roller or cam follower 59 which is adapted to be engaged by cams 60, 61, carried by ring 28. Each cam is located on the ring 28 so that it engages the member 59 just after one of the stylus has left the edge of the strip 4 and just before the other stylus is about to engage the said strip. Thus, during this indexing interval, the arm 55 is forced upwardly to rotate the ratchet wheel 15 a predetermined distance. Wheel 15 being coupled to the flexible shaft 19 also transmits its rotary movement to the feed rollers 8. It will be understood of course that the ratchet wheel 15 is provided with any suitable and well-known means for preventing back-lash and preferably also ratchet wheel 15 is provided with any suitable form of friction brake. Thus, as shown in the drawings, the wheel 15 may be provided with a peripherally grooved shoulder 62 which is encircled by a friction band or cord 63. One end of band 63 may be fastened directly to the bracket 56 and the other end may be fastened to the said bracket through a tension spring 64. The manner of operation of the recorder will be obvious to those familiar with facsimile recording art. Suffice it to say that prior to setting the mechanism in operation, cover plate 45 is removed and one or both of the closure members 41 is removed whereupon the paper roll 36 is inserted within the humidor section 40. The cover plates 41 may then be placed in condition and the paper threaded through opening 43 and then curved transversely until it assumes a substantial semi-circular shape whereupon it may be threaded through the semi-circular slot 3 and upwardly between the members 5 and 28 and between the feed rollers 8 and the idler rollers 16. For this latter purpose, the ring 21 may be rotated to unlock the rollers 16 to facilitate the initial insertion of the strip, whereupon the ring 21 may be rotated in the opposite direction to lock the rollers 16 in place against the

strip. The cover plates 41, 42 and 45 may then be fastened in place. The received telefacsimile signals after suitable amplification and/or detection are impressed across the two stylus 33 and the ring 34 and the motor 47 may be started in operation to revolve the styli around the transversely curved recording strip 4. Assuming that the strip 4 is curved so as to embrace approximately 180° of the surface of ring 5, then each stylus 33 will be arranged to scan or record on successive parallel linear elements of the strip 4. In other words, just as one stylus is leaving the strip 4 and just before the other stylus is about to engage the strip 4, the ratchet wheel 15 is given an impulse to rotate the feeding rollers 8 thus advancing the strip 4 the width of a linear element, whereupon the next stylus is ready to record on the strip. By means of the inclined end of the section 33¹, just as the recording stylus is about to leave the strip 4, it is forced radially outwardly and is maintained in its outer position by the track 33¹. Likewise, just as the other stylus is about to engage the strip 4, it rides off the inclined end of the section 33¹. If the strip 4 embraces more or less than one-half the circumference of the member 6, then the track 33¹ can be correspondingly adjusted by reason of its telescoped character so as to disengage one stylus from the strip 4 during the portion of its rotation where it is not recording. It will be understood of course that the motor 47 is rotated in synchronism with the scanning or analyzing equipment at the transmitter, the styli continuing to rotate and record until the complete message is reproduced on the strip 4. If desired, the entire mechanism may be enclosed in a suitable housing provided with a window in one of its walls past which the strip 4 passes.

While the mechanism for feeding the recording strip 4 has been disclosed above in connection with a recorder wherein the recording is done on the convex peripheral surface of a transversely curved record sheet 4, it will be understood that the invention is equally well applicable to a recorder of the type where the recording is done on the inner or concave surface of the curved strip. For details of such a recorder, reference may be had to my prior application Serial No. 195,486. A typical arrangement of this character is schematically illustrated in Fig. 12 wherein the parts which are similar to those of Fig. 1, bear the corresponding designation numerals. Thus the paper or record strip 4 is threaded through a semi-circular slot 3 in the wall 1 and is maintained against the inner concave face of a ring 65 which has embedded on its inner face a conducting ring 66 similar to the ring 34 (Fig. 1). A suitable curved paper guide or guides 67 may be mounted on the wall 1 to maintain the recording strip 4 in its transverse arcuate curved shape against the inner face of ring 65. The paper 4 is fed or indexed by means of the ratchet wheel 15 which is fastened to the circular flexible shaft 9 which in turn carries the knurled feed rollers 8 as above described. The motor 47 through suitable gearing 49 rotates an arm 67 which carries at each end a stylus 33 in alignment with the electrode 66. For the purpose of indexing the ratchet wheel 15, the motor also rotates an arm 68 which carries the cams 60 and 61 for operating the ratchet 54. The remainder of the embodiment of Fig. 12 may be the same as that of Fig. 1, and further description thereof is not believed necessary. It will be noted that each of the stylus 33

- records on the inner or concave surface of the transversely curved strip 4 and the strip is indexed in a step-by-step fashion during the interval when both of the styli are out of engagement therewith. It will be understood of course that the showing in Fig. 12 is essentially diagrammatic and that the various supports for the parts and the paper supply and humidor are omitted for the sake of clarity in the drawings.
- 10 Various changes and modifications may be made in the disclosed embodiments without departing from the spirit and scope of the invention. For example, while the invention has been described in connection with a recorder of the electro-chemical type, it will be understood that the feeding mechanism and related parts are equally well applicable to recorders of the electro-optical type. For example, the strip 4 may be in the form of a sensitized photographic film and 15 the ring 28 instead of carrying a pair of styli may carry a pair of light sources modulated by the telefacsimile signals, the light sources of course being provided with well-known apertured masks to limit the exposure of the film 4 to successive 20 elemental light spots. It will be understood of course, that with this type of recorder, the entire mechanism must be used in a photographic dark room or enclosed in a light-proof housing. If desired, one or more of the feed rollers 8 may have 25 their surfaces curved or inclined so as to conform to the curvature of the strip 4 and if desired, two oppositely disposed feed rollers may be inclined so that during their feeding movement they tend to maintain the paper taut around the member 30 6 as described in detail in said application Serial No. 195,486. Likewise while the feed rollers 8 are shown disposed on the interior of member 6 and the idler rollers 16 are shown on the exterior of the said member 6, it will be understood 35 that the position of these rollers may be reversed. That is to say, the flexible shaft 9 may be mounted so that it surrounds the outer periphery of the member 6. The feed rollers 8 will then engage the outer surface of the strip 4 and the idler rollers 16 will engage the inner or concave surface 40 of the strip.
- What I claim is:
1. A telefacsimile recorder including a cylindrical drum having a conductive strip electrode insulatingly mounted around the periphery thereof and having its concave surface exposed to the interior of the drum, a shaft mounted substantially concentrically within said drum, a stylus arm extending radially from said shaft and rotatable interiorly of said drum, and a recording stylus carried by the end of said arm facing the concave surface of said strip.
  2. A telefacsimile scanner including a curved support to support a record strip to be scanned, and means to feed said strip along said support comprising a plurality of feed rollers in contact with said strip, a common flexible driving shaft curved to correspond with the curvature of said support and to which all said rollers are fastened for rotation therewith, and means to rotate said flexible shaft to advance said strip.
  3. A telefacsimile scanner including means to form a record strip into a transversely curved shape, and means to feed said strip while in its curved shape past a scanning device, the last-mentioned means including a plurality of feed rollers to engage said strip, said feed rollers being arranged around the curved portion of the strip, a common flexible drive shaft to which said rollers are fastened for rotation therewith, and

means to rotate said flexible shaft to advance said strip.

4. In combination, means to form an elongated strip into transversely curved shape, and means to feed said strip in the direction of its length, the last-mentioned means including a plurality of feed rollers bearing against the sheet, a common curved flexible shaft to which said rollers are fastened for rotation therewith, and means to rotate said flexible shaft to advance said strip. 10

5. In combination, means to form an elongated strip into transversely curved shape, and means to feed said strip in the direction of its length, the last-mentioned means including a plurality of rollers mounted to roll in planes parallel to the feeding movement of said strip, said rollers being mounted so that their axes of rotation are at an angle to each other, a common flexible drive shaft for said rollers and to which said rollers are fastened for rotation therewith, and means to 13 rotate said flexible shaft to advance said strip.

6. In a telefacsimile scanner, a curved support for supporting a record sheet therearound, and means to feed the sheet along the support comprising a plurality of feed rollers engaging the sheet, said rollers being circumferentially spaced around the periphery of said support, a curved flexible drive shaft to which said rollers are fastened for rotation therewith, and means to rotate said flexible shaft to advance said sheet. 25

7. A scanner according to claim 6 in which said feed rollers have roughened driving faces. 30

8. A scanner according to claim 6 in which a pivoted idler roller is mounted adjacent each feed roller to engage the sheet on the opposite side from that engaged by the adjacent feed roller. 35

9. A facsimile scanner comprising a ring electrode, a recording stylus, a carrier for supporting said stylus in coaxial relation around the convex surface of said ring and means to feed a recording web between said stylus and said ring, the last-mentioned means including a curved flexible driving shaft with the same curvature as said ring, and a pawl and ratchet mechanism for rotating said shaft. 40

10. A scanner according to claim 9 in which a rotating cam is rotated with said carrier to operate the pawl and ratchet mechanism in timed relation to the rotation of the recording stylus. 45

11. A scanner according to claim 9 in which said carrier is provided with a cam for operating the pawl and ratchet mechanism. 50

12. A web feeding mechanism for a facsimile scanner comprising means to support the web in transversely curved shape, a plurality of knurled feed rollers surrounding the curved web and engaging one face of said curved web, a curved flexible driving shaft for operating said feed rollers, means to rotate said shaft to advance the web, a plurality of idler rollers mounted adjacent the feed rollers to engage the opposite surface of the curved web, and means to move all the idler rollers as a unit into and out of engagement with the web. 55

13. In a mechanism of the character described, a scanning device having a curved support for a recording web, a pay-off reel for said web, a completely enclosed humidor housing for said reel and for the web between the reel and the scanning device, a curved slot through which said web is fed to said scanning device and means to mount the reel in relation to said slot so that the portion of the web between the reel and slot is offset with respect to said curved support where- 60

by said portion is freely suspended within the housing out of contact with the walls thereof.

14. In a mechanism of the character described, a scanning drum for scanning an elongated record strip while in transversely arcuate form, a pay-off reel for said strip mounted with its axis perpendicular to the axis of said drum, a completely enclosed humidor housing for said reel and for the portion of said strip between the reel and the scanning drum and positioned so that the pay-off portion of the reel is offset laterally with respect to the periphery of said drum whereby said portion of the strip is freely suspended within said housing out of contact with the walls thereof.

15. A facsimile scanner including a curved support to support a record strip to be scanned, a rotatable scanner for scanning the concave surface of said strip, and means to feed said strip along

said support comprising a plurality of feed rollers in contact with said strip, a common curved flexible drive shaft to which said rollers are fastened for rotation therewith, and means to rotate said flexible shaft to advance the strip.

16. A stylus arrangement for a telefacsimile scanner, comprising a stylus support, an arm slidably mounted in said support, said arm carrying a stylus at one end, and a resilient stop for the other end of the said arm, and means for adjusting the position of said stop with respect to said stylus.

17. A stylus arrangement according to claim 16 in which said stop is adjustably carried by a spring support.

18. A stylus according to claim 16 in which the stylus arm carries a curved insulating shoe in which the stylus point is embedded.

ARTHUR C. RUSTAD.
